(57) **CLAIM**

I claim, the ornamental design for a protective cover, as shown and described.

DESCRIPTION

FIG. 1 is a perspective view of a protective cover, showing my new design;

FIG. 2 is a top plan view of the embodiment shown in FIG. 1;

FIG. 3 is a bottom plan view of the embodiment shown in FIG. 1;

FIG. 4 is a side elevation view of the embodiment shown in FIG. 1;

FIG. 5 is another side elevation view of the embodiment shown in FIG. 1;

FIG. 6 is a front elevation view of the embodiment shown in FIG. 1; and,

FIG. 7 is a back elevation view of the embodiment shown in FIG. 1.

The stipple shaded portion in FIGS. 1-6 is understood to represent a difference in material between portions of the design.

The broken lines in the drawings are for the purpose of illustrating portions of the article and form no part of the claim.
